CLAIM

The ornamental design for a cookie dunking device, as shown and described.

DESCRIPTION

FIG. 1 is a top front perspective view of a cookie dunking device showing my new design;

FIG. 2 is a bottom rear perspective view thereof;

FIG. 3 is a top plan view thereof;

FIG. 4 is a bottom plan view thereof;

FIG. 5 is a left side elevation view thereof;

FIG. 6 is a front elevation view thereof;

FIG. 7 is a rear elevation view thereof; and,

FIG. 8 is a top front perspective view of the cooking dunking device, shown in an environment of use.

The broken lines shown in FIG. 8 represent environment and form no part of the claimed design.

1 Claim, 4 Drawing Sheets(56)
